[57] CLAIM

The ornamental design for an activity toy, as shown and described.

DESCRIPTION

FIG. 1 is a perspective view of an activity toy showing my new design;

FIG. 2 is a top plan view thereof;

FIG. 3 is a front elevational view thereof;

FIG. 4 is a right side elevational view thereof, the left side elevational view being a substantial mirror image thereof;

FIG. 5 is a rear elevational view thereof; and

FIG. 6 is a bottom plan view thereof.

The broken line showing of the strap member is for illustrative purposes only and forms no part of the claimed design.
